CLAIM

The ornamental design for a scent dispenser, as shown and described.

DESCRIPTION

FIG. 1 is a front view showing the new design.

FIG. 2 is a back view showing the new design.

FIG. 3 is a top plan view showing the new design.

FIG. 4 is a bottom view showing the new design.

FIG. 5 is a left side view showing the new design, the right side view being a mirror image of the left side view.

FIG. 6 is a front, right perspective view showing the new design.

FIG. 7 is a back, left view showing the new design; and, FIG. 8 is a top, front, left perspective view showing the new design.

Within the drawings, the dashed lines show unclaimed portions of the scent dispenser, and form no part of the claimed design.

1 Claim, 8 Drawing Sheets
